UNITED STATES PATENT OFFICE.

WILLIAM YOUNG, OF PEEBLES, SCOTLAND, AND SAMUEL GLOVER, OF ST. HELENS, ENGLAND.

PROCESS OF CARBONIZING COAL.

No. 876,420.

Specification of Letters Patent.

Patented Jan. 14, 1908.

Application filed November 13, 1906. Serial No. 343,268.

To all whom it may concern:

Be it known that we, WILLIAM YOUNG and SAMUEL GLOVER, subjects of the King of the United Kingdom of Great Britain and 5 Ireland, and residing at Peebles, Scotland, and St. Helens, Lancashire, England, respectively, have invented certain new and useful Improvements in the Process of Carbonizing Coals for the Production of Illuminating and 10 Heating Gases, of which the following is a specification.

This invention relates to the destructive distillation, or carbonization of coal for the production of illuminating and heating gases 15 and more particularly consists in an improved method of applying the heat necessary for the carbonizing process, whereby such heat is more effectively and economically utilized and better results obtained.

20 The invention is based upon the principle that when coals are carbonized the conditions should be such that the volatile matters will be eliminated from the coals without having to pass through and come into contact with highly heated surfaces, and that the volatile matters after being eliminated will be decomposed or gasified by the action 25 of radiant heat of a suitable temperature. Contact with the highly heated surfaces should be avoided as far as possible, as such contact is destructive indiscriminately, injuriously cracking up the hydrocarbon vapors evolved from the coal the carbon of the 30 constitution of which is largely deposited upon the heated surfaces while naphthalene and other objectionable compounds are produced, and the resulting gases have in consequence a lower illuminating power. On the other hand radiant heat is selective in 35 its action, decomposing the more complex vapors most actively, and in such a manner as to produce gas of a high quality.

40 By the decomposition or cracking up of the vapors from the coal by radiant heat it results that the carbon which is necessarily set free during the gasifying process will be in a very flocculent condition. With the carbonizing apparatus hitherto employed such carbon is carried forward in the current 45 of gas, and is deposited in the stand pipes, hydraulic or other collecting mains, giving much trouble. Further in retorting arrangements hitherto employed for the carbonizing of coal the temperatures to which the retorts 50 are brought to effect the elimination of the

volatile matters from the coal, and to effect the subsequent cracking up or gasifying of the volatile matters being the same, it has been found necessary in practice to adjust the weight of the charge of coal in the 60 retorts, in relation to the size of the vacant space over the charge so that sufficient volatile matter may be left ungasified, and sufficient condensable tar may be produced to wash down and prevent trouble from that 65 flocculent sooty deposit in the stand pipes &c.

Under our invention we employ carbonizing apparatus so arranged that different sections of the retorts will be heated to different temperatures (i. e. of 2190° F. and 2150° F.) 70 in such a manner that the volatile matters are as rapidly as possible destructively distilled out of the coal progressively and so that they are evolved from the coal without being exposed to over highly heated surfaces in one 75 section of the retort, the volatile matters so evolved being subjected in another section of the retort at a lower temperature i. e. about 2,100° F., to the action of radiant heat suitable to decompose them into permanent gas 80 of good quality, while the flocculent carbon and sooty tar set free by the action of the radiant heat are filtered out and separated from the resulting gaseous matters by causing them on leaving the retorts on their way 85 to the collecting main to pass through the fresh charge of coal contained in the hopper before it is charged into the retort. The hot gaseous products are not only filtered free from flocculent carbon and the grosser suspended tar, but there is also at the same 90 time an advantageous exchange of heat, the gases being cooled without separate condensing plant and the coal being heated and so prepared to undergo the carbonizing process; 95 besides this the tarry matters previously deposited upon the coal, on entering the retorts, are gasified; thus slightly adding to the volume of the gas and improving the residual coke.

100 This improved carbonizing process can be most advantageously carried out in vertical or highly inclined retorts, but may in part be applied to other forms of apparatus.

Each retort is provided with a supply hopper from which the coal is fed into the retort, and a discharging chamber from which the coke resulting from the carbonizing of the coal is discharged. The coal may be fed continuously into the retort, and the coke con- 110

tinuously discharged or the coal may be passed into the retort in intermittent charges and the resulting coke similarly discharged; the charging hoppers and discharging chambers being provided with suitable appliances to carry out either method as desired and as found best suited for the carbonization of the particular coal to be gasified.

The retorts are placed in settings of any convenient number and are heated by producer gas, while a regulated quantity of secondary air passes through suitable flue arrangements, whereby the sections of the retorts in which the coal is destructively distilled are heated to a very high temperature, highest at the base of the charge, so that the volatile matters will be eliminated from the coal as rapidly as possible and pass inwards away from the highly heated walls of the retorts and upwards through among the cooler interstices in the center of the charge of coals to emerge finally from the upper surface into the higher section of the retorts, which is purposely heated by the producer gases to a lower temperature. The gaseous products thus gasified pass away by a suitable outlet from the retort into the hoppers containing the fresh charge of coal, through which they pass, being filtered free from sooty tarry matters, and an exchange of heat effected.

The apparatus employed in carrying out the invention is exemplified in the accompanying drawings in which

35 Figures 1, 2 and 3 show in vertical section the upper, the middle and the lower parts respectively of a set of vertical retorts and accessories for use in carbonizing coals, the retorts being represented as divided into 40 three parts for convenience of maintaining a suitable scale of drawing.

As herein represented the retorts are built up of fire brick or formed with a fire brick lining A A around which are formed heating flues B B heated by the combustion of producer gas upon admixture with air. The brick-work is carried by hollow girders C supported by pillars D and occasional piers of brick-work. The coals to be carbonized are 50 delivered by means of conveyers E into large open hoppers F of which one is provided for a number of retorts, the hoppers being supported by upward extensions of the pillars D¹. At its lower end each hopper is fitted 55 with gas tight valves F¹ through which the coals are delivered into a number of measuring hoppers G of which one is provided for each pair of retorts, and from these hoppers G the coals are dropped on opening a bell valve G¹ (operated by a lever handle G²) into a drying chamber H in which they are subjected to the heat of the gas generated below and which in passing up through the chamber deposits tarry matter on the coals. At 60 the bottom of this chamber H the coals are

discharged in regulated streams by means of devices such as the arms H¹ carried on shafts H² and arranged to sweep the coals off the surfaces of tables H³. This device is well known in apparatus for retorting shale and need not be particularly described. From the tables H³ the coals drop into the retorts A which are filled to about four fifths of their height, a free space being left above wherein the gas generated is subjected to radiant heat of a temperature of about 2100° F. in its passage upwards to the drying chamber H.

The coke or carbonized coal after parting with its gaseous constituents descends to the bottom of the retorts A and is continuously or intermittently withdrawn by means of combined right and left hand screws I carried on a rotating shaft I¹, the devices being of a type commonly used in shale retorts, the coke dropping over the ends of inclined plates I² into a discharging hopper J fitted with a bell valve J¹ which is periodically opened by means of a hand wheel shaft J² connected through worm gearing J³ with a shaft J⁴ provided with a chain pulley J⁵ and chain J⁶ attached to the valve. The coke so discharged falls into a wagon K running on rails below.

For the purpose of slaking the coke and keeping cool the screws which draw it from the retorts and other parts of the apparatus water is delivered from a water main S through piping e into the hollow girders C and is discharged through a number of orifices c¹ in proximity to the screws I. The steam thus formed passes up through and among the hot coke and charge of coal in the retorts to assist in the production of water gas and ammonia.

The carbonization of the coals within the 105 retorts A is effected by the combustion of producer gas and air, the gas being supplied through a main L furnished with suitable valves L¹ and being led by a conduit to a flue L² in the lower part of the brickwork of the 110 retorts, while the air which is heated by traversing a regenerator flue is admitted through a flue M to a flue M¹ just over the gas flue L², each of these flues being provided with a movable damper or other closure l for 115 regulating the admission.

The mixed gas and air are directed into and through the heating flues B B which are fitted with suitable baffles so that the burning gas is caused to travel entirely around the lower part of the retorts, thence around one section after another at higher levels.

The various parts of the retorts are subjected to different temperatures and to insure regulation of the temperature the secondary air to complete the combustion of the heating gas is admitted by flues M² provided with suitable dampers l¹ at various levels. The heat transmitted into the space above the coals in the retorts is less intense than 130

that at the lower levels where carbonization is effected and is regulated to insure fractional cracking up of the gas evolved as already described.

5 The waste gases resulting from the combustion of the producer gas in the heating flues pass into an outlet flue O and down through the brickwork to a main discharge flue O¹ under the ground level. The gas generated by 10 carbonization of the coals passes up through the fresh coal in the drying chamber H where tarry and flocculent matters are deposited on the coal, and thence the gas is led by a bridge pipe P to the usual hydraulic 15 main P¹.

Steam or water gas or both may be directed through the retorts from a main Q having pipe connections Q¹ to the discharge hopper J up through the coke in which the 20 steam or water gas or both flow on their way to and up through the retorts.

When it is desired to enrich the gas, liquid hydrocarbon may be directed into the retorts A through suitable inlets as in the drying chamber at R.

Having now described our invention what

we claim and desire to secure by Letters Patent of the United States is:—

The herein-described process of producing illuminating and heating gases by the carbonization of coals and like bituminous material, consisting in distilling a charge of coal, subjecting the volatile matters evolved therefrom to the action of radiant heat, causing the degree of said radiant heat to be gradually reduced along the route over which the volatile matters travel, whereby the same will be decomposed to form fixed gases and liberate carbon, and passing the gases through a mass of coal so as to cool the 40 gases and heat the coal, causing the coal to fall into the heated area, and drawing off the gases so cooled.

In testimony whereof we have signed our names to this specification in the presence of 45 two subscribing witnesses.

WM. YOUNG.
SAMUEL GLOVER.
